CLAIM

The ornamental design for a pet chew, as shown and described.

DESCRIPTION

FIG. 1 is a front, top and right side perspective view of a pet chew, showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The break lines shown in the middle portion of the pet chew in FIGS. 1 and 4-7 indicate that the appearance of any portion of the article between the break lines form no part of the claimed design.
